CASING FOR A CALCULATING MACHINE OR SIMILAR ARTICLE

Myron Beitler, West Orange, and Jeffrey M. Chambers,
Willingboro, N.J., assignors to Litton Business Systems,
Inc., Orange, N.J., a corporation of New York

Filed Oct. 13, 1969, Ser. No. 19,543

Term of patent 14 years

Int. Cl. D18—01

U.S. Cl. D64—11

FIG. 1

FIG. 2

Des. 219,116

PAGE 2

FIG. 3

FIG. 4

FIG. 5

FIG. 1 is a front perspective view of a casing for a calculating machine or similar article;

FIG. 2 is a front elevational view thereof;

FIG. 3 is a top plan view thereof;

FIG. 4 is a right side elevational view thereof, the left side being substantially similar in appearance; and

FIG. 5 is a rear elevational view thereof.

We claim:

The ornamental design for a casing for a calculating machine or similar article, as shown and described.
